N. D. NACHTRIEB

TEMPORARY BINDER RING

Filed Nov. 24, 1922

Inventor:

Norman D. Nachtrieb,
By Dreyfuss, Jr., Clinton, Miles
Attys.

UNITED STATES PATENT OFFICE.

NORMAN D. NACHTRIEB, OF CHICAGO, ILLINOIS, ASSIGNOR TO HENRY T. ADAMS, OF CHICAGO, ILLINOIS.

TEMPORARY BINDER RING.

Application filed November 24, 1922. Serial No. 602,969.

To all whom it may concern:

Be it known that I, NORMAN D. NACHTRIEB, a citizen of the United States, residing at Chicago, in the county of Cook and State of Illinois, have invented a new and useful Improvement in Temporary Binder Rings, of which the following is a specification.

This invention relates to improvements in temporary binder rings, which are especially designed for use in connection with loose-leaf books and the like, in which a cover having a flexible back with metal eyelets therein is employed, such eyelets serving to receive the metal rings which in turn retain the loose sheets of paper, or the like, within the covers of the binder. It is an obvious fact that the rings are also adapted for a multitude of other uses. For example, the rings may be used for retaining keys or other articles.

The ring here shown constitutes an improvement over the rings shown in prior Patents Nos. 692,584 and 1,331,226.

In that form of device embodying the features of my invention, shown in the accompanying drawings, Figure 1 is a plan view, on an enlarged scale, showing the ring partially open, Fig. 2 is a view taken as indicated by the line 2 of Fig. 1, Fig. 3 is an enlarged broken view illustrating the manner in which the ring sections meet at their free ends as the ring is being closed, and Fig. 4 is a similar view showing the free ends of the ring sections in interlocked position.

The binder ring shown comprises a ring section A, provided with a hinge portion A'; and a ring section B, provided with the hinge portion B', the hinge portions being secured together by means of a rivet 1.

The ring sections are made preferably of steel wire of round cross section, the metal of each ring section being flattened at one end to form the hinge portion; so that the hinge will be of approximately the same thickness as the wire which forms the ring sections. Also, in the operation of forming the hinge portions, provision is made for causing the ring sections to occupy normally divergent planes, as will be understood from Figs. 2 and 3. This is accomplished preferably by so swaging the metal by means of the dies in forming the hinge portions, as to make the hinge portions

somewhat tapering in cross section. Thus, as indicated in Fig. 2, the inner edge 3 of each hinge portion is thicker than the outer edge 3^a. The effect is, when the hinge portions are brought together with their inner faces occupying a central plane, to throw the ring sections A and B in opposite directions from the central plane, as most clearly indicated in Fig. 2.

The ring sections are provided at their free-end portions with interlock notches 4 and 5, as shown in Fig. 3, similar to the notches shown in the rings disclosed in the patents above referred to. Thus, the ring section A is provided near its extremity with a transverse interlock notch 4, flanked on one side by a slanting shoulder 4^a and on the other side by a projection 4^b, the projection 4^b being at the extreme end of the ring section and having its end face or surface beveled or slanting, as indicated by 4^c, thus serving to make the end face or surface of the ring section A wedge-shaped, beveled, or slanting. The metal of the ring section is cut away at its extremity, as indicated at 4^d. Similarly the member B is provided with an interlock notch 5 flanked by a slanting shoulder 5^a and a projection 5^b. The projection 5^b is at the extreme end of the ring section and has its end face or surface beveled or slanting, as indicated by 5^c, thus serving to make the end face or surface of the ring section B wedge-shaped, beveled or slanting. The end of this ring section B is also cut away at its extremity, as indicated at 5^d.

The ring sections are so formed that as the ends A and B are brought together, the slanting faces 4^d and 5^d will normally slightly overlap, as indicated at 71. When it is desired to close the ring, the ends A and B are forced toward each other. The slanting surfaces 4^d and 5^d will thus serve to move the ring sections from the divergent planes, in which they normally lie, into the same plane and then slightly beyond until the surfaces 4^e and 5^e slip past each other and the ends of the ring spring into the interlocked position, shown in Fig. 4. In other words, as the ends of the ring sections are brought together, they will normally meet, as shown in Fig. 3. Pressure applied to the ring sections will then cause the slanting faces 4^d and 5^d on the ends of the ring sections to slide on each other 110

until the surfaces 4^c and 5^c become adjacent. These surfaces 4^c and 5^c will then slide on each other until the projection 4^b springs into the notch 5 and the projection 5^b springs into the notch 4, thus interlocking the rings, as shown in Fig. 4.

The surfaces of the projections 4^b and 5^b lying adjacent the notches 4 and 5 respectively, are preferably slightly undercut, as indicated at 4^e and 5^e, respectively. This undercutting or bevelling of these surfaces assists in retaining the ends of the ring in interlocked position.

While I have shown and described certain embodiments of my invention, it is to be understood that it is capable of many modifications. Changes, therefore, in the construction and arrangement may be made without departing from the spirit and scope 15 of the invention as disclosed in the appended claim, in which it is my intention to claim all novelty inherent in my invention

as broadly as possible in view of the prior art.

What I claim as new and desire to secure by Letters Patent, is:

A ring of the character described, comprising a pair of ring sections having flattened tapered pivotally connected end portions whereby the free ends are offset a portion of the thickness thereof when separated, complementary hook-shaped extremities upon the free ends of said sections each extremity comprising a beveled outer surface and a base parallel therewith, a shank 30 of substantial length and a hook having its rear engaging surface undercut adjacent said shank whereby separating stresses upon said ring while closed will tighten the engagement of said extremities.

Witness my hand and seal this 21st day of November, 1922.

NORMAN D. NACHTRIEB. [L.S.]
